CLAIM

The ornamental design for a lunch bag, as shown and described.

DESCRIPTION

FIG. 1 is a front, right perspective view of a lunch bag, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof; and,

FIG. 8 is an enlarged view of a circle labeled 8 in FIG. 1 of the lunch bag.

The details shown in broken lines form no part of the claimed design.
